CYLINDER HONE

Harold P. Phillips, Hastings, Mich., assignor to
 Hastings Manufacturing Company, Hastings,
 Mich.

Application February 4, 1952, Serial No. 269,821

7 Claims. (Cl. 51—184.3)

1

This invention relates to improvements in cylinder hones.

The main objects of this invention are:

First, to provide a cylinder hone which is well adapted for deglazing internal combustion engine cylinders, and is capable of being used in an engine installed in a motor vehicle, even when it is overhung by other parts and direct access to the cylinder is not possible.

Second, to provide a cylinder hone which is well adapted for the deglazing of cylinders and which may be effectively used even when the operator must work well to one side of the cylinder operated upon.

Third, to provide a cylinder hone having these advantages and which also has the advantage of the hones and wiper blades with which it is equipped being mounted to permit automatic adjustment to a cylinder wall which has been worn tapered or out-of-round, and at the same time they are effectively supported for performing their functions.

Objects relating to details and economies of the invention will appear from the description to follow. The invention is pointed out in the claims.

A preferred embodiment of the invention is illustrated in the accompanying drawings, in which:

Fig. 1 is a perspective view of a structure embodying my invention, parts being broken away to show structural details.

Fig. 2 is an elevational view partially in section illustrating an engine block in relation to parts of an automobile body with the hone of my invention shown in one operative position, a driving unit being shown conventionally by dotted lines.

Fig. 3 is an enlarged fragmentary view in section on a line corresponding to lines 3—3 of Fig. 4 with the hone in operative relation with a cylinder as shown in Fig. 2.

Fig. 4 is a fragmentary view mainly in longitudinal section on a line corresponding to broken line 4—4 in Fig. 3.

In the accompanying drawing 1 represents a cylinder block and 2 a wall portion of the engine housing having a portion 3 overhanging a portion of the cylinder block 4.

The embodiment of my invention illustrated comprises a head member 5 having axially spaced crossheads 6 carrying the angularly spaced pivots 7 for the holder arms 8. In this embodiment there are four of these arms. The pivots 7 are parallel to the axis of the head or body member.

2

The body member is provided with a shank 9 which is externally threaded and has an internally threaded bore 10. The holder arms 8 have slots 11 in their outer ends in which the flanges 12 of the tool holders 13 are tiltably mounted as by means of the pivots 14. The inner edges 15 of the holders 12 are slightly spaced from the bottoms of the slots as shown in Fig. 3 to permit limited axial tilting movement thereof.

10 the purpose of which will be pointed out later.

Each holder arm is provided with a supporting pin 16, the pins being engaged with the arms in spaced relation to their pivots. These pins are in supporting engagement with the adjusting cone 18. The pins are resiliently springable to permit the blades to conform to out-of-round cylinders. The adjusting cone is threaded upon the shank of the head member and is desirably knurled at 19 to facilitate grasping. The pins 20 are yieldingly urged against the adjusting cone by means of the springs 20 which are connected at one end to the pins and at the other end to the pivots 7 which are extended at their outer ends to constitute anchoring studs for the springs 25 as shown in Figs. 3 and 4.

In the embodiment illustrated I show two hone blades 23 and two wiper blades 24, these being mounted in alternating relation on the holders. The hone blades are desirably of a 30 suitable grade of Carborundum or the like, while the wiper blades are rectangular sections of felt, desirably quite compact or hard felt.

The drive shaft designated generally by the numeral 25 comprises an outer rigid or relatively unbendable section 26 having a tang 27 at its outer end adapted to be engaged with the chuck 28 of a portable electric drill 29 or the like. The inner bendable section 30 of the shaft is resiliently bendable and consists of a section 40 of rubber hose 31 reinforced by fabric 32 and wire strands 33 as is conventionally illustrated, see Fig. 4. The tubular element 31 is fixedly connected by the coupling 34 to the outer section 26 and is provided with a coupling 37 which is 45 pinned thereto at 38 and has a threaded tang 39 threaded into the shank of the head member, the coupling having a shoulder 40 abutting the end of the shank.

To prevent collapsing and buckling of the tubular element 30 of the bendable section of the shaft I insert therein a helically coiled spring 41. The spring is a close fit within the element 30 but is not connected thereto other than being in supporting engagement with the walls thereof. 55 The spring 41 is closely coiled and prevents the

collapsing of the wall and sharp buckling or kinking of the section 30 as it is bent and torsional stress is applied thereto. The spring also tends to straighten the element 30 after it has been flexed or bent. The ends of the spring are not connected to the coupling members 26 and 37 but are desirably in end thrust supported engagement therewith.

It is a matter of common observation that cylinders of internal combustion engines become glazed as a result of use so that when new piston rings are installed they do not "wear in" promptly or effectively, and various means have been resorted to to remove or score the glaze. Cylinder hones are one means that has been used for that purpose. While the applicant's hone is desirable for use in hone finishing cylinders, it is particularly desirable for use in deglazing cylinders in installed engines, particularly where certain of the cylinders may be located so that direct access cannot be had thereto. The hone blades and wiper blades of this invention are mounted and supported so that they effectively conform to the cylinder wall, but remove the glaze and the high spots which commonly result or come about from the distortion and seasoning of the cast iron cylinder block in use. The flexible shaft permits the hone to follow the cylinder wall without any substantial canting stress on the hone, and it permits the use of the hone in situations such as is illustrated conventionally in Fig. 2.

I have illustrated and described my invention in a highly practical commercial embodiment thereof. I have not attempted to illustrate or describe other adaptations or embodiments which I contemplate as I believe this disclosure will enable those skilled in the art to embody the invention as may be desired.

Having thus described my invention, what I claim is new and desire to secure by Letters Patent is:

1. In a cylinder hone the combination of a head member provided with a shank and with axially spaced cross heads, angularly spaced tool arm pivots extending between said cross heads and disposed in parallel relation to the axis of the head member, holder arms mounted on said pivots between and axially supported by said cross heads, holders pivotally mounted on the outer ends of said arms for limited axial tilting movement thereon, hone and wiper blades mounted on said holders in alternating relation to each other, an inwardly facing adjusting cone adjustably threaded on said body member shank, springable supporting pins on said arms adjustably supported by said cone, retracting springs for said arms connected at one end to the said pins and at the other to the said head member, a drive shaft for said head member comprising a substantially rigid outer chuck engaging spindle section, and an inner resiliently bendable tubular section of substantial length connected to said head member shank and to said outer spindle section and comprising a section of wire reinforced hose, and a closely coiled helical spring fittingly disposed within said inner section and extending from end to end thereof in wall supporting but non-torsional relation thereto.

2. In a cylinder hone the combination of a head member provided with a shank and with axially spaced cross heads, angularly spaced tool arm pivots extending between said cross heads and disposed in parallel relation to the

axis of the head member, holder arms mounted on said pivots between and axially supported by said cross heads, holders pivotally mounted on the outer ends of said arms for limited axial tilting movement thereon, hone and wiper blades mounted on said holders in alternating relation to each other, an inwardly facing adjusting cone adjustably threaded on said body member shank, springable supporting pins on said arms adjustably supported by said cone, retracting springs for said arms connected at one end to the said pins and at the other to the said head member, a drive shaft for said head member comprising a substantially rigid outer chuck engaging spindle section, and an inner resiliently bendable section of substantial length connected to said head member shank and to said outer spindle section.

3. In a cylinder hone the combination of a head member provided with a shank and with axially spaced cross heads, angularly spaced tool arm pivots extending between said cross heads and disposed in parallel relation to the axis of the head member, holder arms mounted on said pivots between and axially supported by said cross heads, holders pivotally mounted on the outer ends of said arms for limited axial tilting movement thereon, hone and wiper blades mounted on said holders in alternating relation to each other, an inwardly facing adjusting cone adjustably threaded on said body member shank, springable supporting pins on said arms adjustably supported by said cone, retracting springs for said arms connected at one end to the said pins and at the other to the said head member, and a drive shaft connected to said head member.

4. In a cylinder hone the combination of a head member provided with a shank, angularly spaced tool arm pivots carried by said head member and disposed in parallel relation to the axis of the head member, holder arms mounted on said pivots, holders mounted on the outer ends of said arms for limited axial tilting movement, tool blades on said holders, an inwardly facing adjusting cone adjustably threaded on said body member shank, springable supporting pins on said arms adjustably supported by said cone, retracting spring for said arms carried by said head member, a drive shaft for said head member comprising a substantially rigid outer section, and an inner bendably resilient tubular section of substantial length connected to said head member shank and to said outer section and comprising a section of torsion transmitting hose, and a closely coiled helical spring disposed within said inner section and extending from end to end thereof in wall supporting non-torsional relation thereto.

5. In a cylinder hone the combination of a head member provided with a shank, angularly spaced tool arm pivots carried by said head member and disposed in parallel relation to the axis of the head member, holder arms mounted on said pivots, holders mounted on the outer ends of said arms for limited axial tilting movement, tool blades on said holders, an inwardly facing adjusting cone adjustably threaded on said body member shank, springable supporting pins on said arms adjustably supported by said cone, retracting spring for said arms carried by said head member, a drive shaft for said head member comprising a substantially rigid outer section, and an inner bendably resilient section of substantial length connected to said head member shank and to said outer section.

6. In a cylinder hone the combination of a head member having axially spaced cross heads, angularly spaced tool arm pivots extending between said cross heads and disposed in parallel relation to the axis of the head member, holder arms mounted on said pivots between and axially supported by said cross heads, holders pivotally mounted on the outer ends of said arms for limited axial tilting movement thereon, hone and wiper blades mounted on said holders in alternating relation to each other, an inwardly facing adjusting cone adjustably threaded on said body member shank, springable supporting pins on said arms adjustably supported by said cone, retracting springs for said arms carried by said head member, a drive shaft for said head member comprising a substantially rigid outer section, and an inner bendably resilient tubular section of substantial length connected to said head member shank and to said outer section and comprising a section of reinforced hose, and a closely coiled helical spring disposed within said inner section and extending from end to end thereof in wall supporting non-torsional relation thereto.

7. In a cylinder hone the combination of a head member having axially spaced cross heads, angularly spaced tool arm pivots extending between said cross heads and disposed in parallel relation to the axis of the head member, holder

arms mounted on said pivots between and axially supported by said cross heads, holders pivotally mounted on the outer ends of said arms for limited axial tilting movement thereon, hone and wiper blades mounted on said holders in alternating relation to each other, an inwardly facing adjusting cone adjustably threaded on said body member shank, springable supporting pins on said arms adjustably supported by said cone, retracting springs for said arms carried by said head member, a drive shaft for said head member comprising a substantially rigid outer section, and an inner section of substantial length connected to said head member shank and to said outer section.
